L. M. EVETTE

KEYED WIND INSTRUMENT

Filed Oct. 24, 1921

UNITED STATES PATENT OFFICE.

LEON MAURICE EVETTE, OF PARIS, FRANCE, ASSIGNOR TO SOCIETE EVETTE AND SCHAEFFER, OF PARIS, FRANCE, A COMPANY OF THE FRENCH REPUBLIC.

KEYED WIND INSTRUMENT.

Application filed October 24, 1921. Serial No. 510,051.

To all whom it may concern:

Be it known that I, LEON MAURICE EVETTE, citizen of the French Republic, residing at Paris, Department of the Seine, in France, and having P. O. address 18 Passage du Grand Cerf, in the said city, have invented certain new and useful Improvements in or Relating to Keyed Wind Instruments; and I do hereby declare the following to be a full, clear, and exact description of the invention, such as will enable others skilled in the art to which it appertains to make and use the same.

The present invention relates to keyed musical wind instruments, such as clarinets, saxophones, oboes, etc., built on principles which are somewhat similar to the Boehm system of clarinets.

Heretofore the forked E flat B flat would be given either by means of a perforated plate or by means of a ring having near it a tuning hole; it was impossible on the same instrument to produce at will C—E flat (G—B flat) and D flat E flat (A flat B flat) with facility and absolute accuracy.

In order to overcome this inconvenience, I have provided a mechanism which permits of giving with perfect accuracy the trills C—E flat (G—B flat) D flat E flat (A flat B flat) and with the same fingering, that is to say, by raising and lowering the middle finger of the left hand.

The invention has for its object to obtain in an instrument as above, and with the exactitude both for the fundamental notes and for the harmonics a rapid and easy slur from the note E flat B flat given by raising the left middle finger (third or ring finger, index and thumb being lowered) to the notes C sharp G sharp and C—G sounded through the holes situated at intervals of a semi-tone and tone below that covered by the left ring finger, such slur being facilitated for E flat C sharp by means of the automatic elevation in certain circumstances hereinafter explained of the pad situated at an interval of one semi-tone below the hole controlled by the third or ring finger of the left hand such pad lying over the hole emitting C sharp.

Some examples of mechanism in accordance with the present invention which mechanism permits of obtaining the desired results, are shown diagrammatically in Fig-

ures 1 to 13. These mechanisms are shown applied to a clarinet, it being understood that the mechanism of all clarinets is not generally the same. The mechanism of Figures 1 and 2 comprises an eccentric, that of Figures 3 and 4 comprises only levers. Figures 5 and 6, and 7, 8 and 9 show details of these mechanisms separated for clearness of description.

Figures 10, 11, 12 and 13 show a modified form of the mechanism indicated in Figure 3.

In clarinets, the hole situated at an interval of one semi-tone below the hole closed by the left hand ring finger is that which emits the fundamental note C sharp and its harmonic G sharp. Hitherto this hole in all types of clarinets has been usually, though not always, held blocked by a pad maintained in the "down" position by a single spring, when the key is in one piece, and by a counter spring which is contrary to the action of the former spring when the key is turned and articulated.

In the mechanism in accordance with the present invention the hole for C sharp is on the contrary held open until the left middle finger closes the hole E flat. When the hole E flat is closed, the hole C sharp is closed but may be opened by its key. Mechanism may also be added by which depression of the rings of the right hand fingers in all or some circumstances closes the C sharp pad.

Referring to Figures 1, 2, 5 and 6, the mechanism relates to the case where the key of C sharp, G sharp is in one piece and a spring is arranged under the key. The pad of C sharp is indicated at 1 and the key therefor at 2. In Figure 1 of the drawings the mechanism is shown as a developed plan so as to render the description clearer. The pad and the key are rigidly secured to a spindle 6, Figures 1 and 2, situated in the same plane and below the pivot for the rings of the left hand. These rings form part of a mechanism comprising two pieces with concentric hinges 4 and 3, the one comprising the ring 8 of the hole for the note D and the pad 9 for the hole E natural and the other the finger ring or plate 5 for the hole E flat. The bridge piece 4', Figure 5, allows of the finger ring 5 actuating the ring 8 and the plate 9. On the hinge 3 which is rigid

with the finger ring 5 is keyed a small eccentric 7, Figures 1 and 2, which can affect the C sharp 1 by reason of a stop piece 6' rigid with the rotatable stem 6 of the key of the 5 pad so as to annul the effect of the spring of this key by maintaining the pad raised until the ring 5 is depressed.

In a modified form the mechanism may comprise a lever instead of a lug such as 7, 10 actuated by the ring of the middle finger of the left hand which lever would similarly cause the elevation of the pad of C sharp, G sharp every time that the said ring or plate is raised.

15 In the second arrangement, Figures 3, 4, 7, 8 and 9, the pad 1 is not rigid with its key 10 but the key is mounted separately on an axis 11, which is formed with a small lever arm 12 rigid with 11, which acts on 20 the pad supported by a part 12' provided on the upper face of the pad in the example shown, but the arm 12 could obviously be caused to act at any suitable point of the mechanism carrying the pad of C 25 sharp, G sharp.

The axis 3 rigid with the disc 5, Figure 3, has fixed to it also a bell crank lever 16 called "correspondence or duplicate" already provided on existing clarinets.

30 This bell crank lever is provided with a recess 16, Figure 9, in which the end of the lever 13 engages which lever 13 is rigid with the axis 14 and with the pad 1 of C sharp, G sharp. The aforesaid bell crank 35 lever 15 which is rigid with the axis 3 and the ring 5 and oppositely movable to the latter is lowered each time the disc 5 is raised and in this movement it causes the end of the lever 13 to engage the recess 16, 40 which causes elevation of the pad of C sharp and compression of a spring under the key 10. Closing the ring 5 allows the spring under the key 10 to close the pad 1 which may, however, be permitted to open by depressing the key 10, a spring being arranged 45 under the pad arm or equivalently.

The usual means of communication of the rings of the bottom part of the body has for its effect to raise the end of the 50 lever 13 by a part 16' (Figures 8 and 9) closing by this means the pad C sharp, G sharp.

Figures 10, 11, 12 and 13 indicate a modified form of the preceding arrangement, the 55 same reference numerals corresponding to like parts in the two arrangements.

In this construction, 17 is an auxiliary arm (Figures 10 and 12) situated on the instrument either above or below the pad 1, which closes this pad arm independently (a weak spring tending to open the pad) and which is pivotally disposed on the same axis as (but turning separately from) the hinge 14 or disposed on any other axis, and 65 which by the action of its cooperating spring

which tends to hold the arm down counteracts that of the pad 1 and consequently maintains the pad in the "down" position as long as the ring or disc 5 is itself maintained in the "down" position so that the 70 crank 15 is raised.

In the mechanism above described the small arm 17 acts on the upper face of the pad, but it would be easy to cause it to act on any suitable part of this pad as, for example, by a tappet arm placed near the hinge or by any other suitable means.

The key 10 fixed to the axis 11 comprises a small arm projecting from the lever 12', one end of which is extended below the arm 17. When the pad is lowered, it is sufficient in order to open the pad to press on the key 10 which by means of the lever 12' raises the arm 17 independently and thus frees the pad 1 which is raised by the action of its spring.

The details of construction set out for the preceding mechanism, Figure 3, apply except as regards the arms 12' and 17 to this modified form.

In the three constructions already described when one of the discs or rings is maintained in the "down" position by the fingers of the right hand or the middle finger of the left hand, the pad is applied to the hole of C sharp, G sharp. As soon as the action of all of these fingers is removed from the mechanism indicated above the pad of C sharp, G sharp is raised.

This modification in the construction of the instrument permits of trilling by oscillating the middle finger of the left hand and either keeping open by the usual finger key the pad C, G or with the little finger of the left hand keeping open C sharp, G sharp, yielding in the former case C-E flat, G-B flat, in the second case D flat E flat and the harmonics A flat, B flat and in the two cases respectively in the highest register E-G, F-G.

This result which heretofore is not found in any one instrument permits of sounding the E flat pitch on clarinets (note emitted by the hole uncovered by the raised middle finger, the other fingers of the left hand being lowered) with the pad of C sharp, G sharp raised (note situated a semi-tone lower than the hole for the ring finger of the left hand).

The effect obtained in clarinets by means of the aforesaid mechanism which raises the pad of C sharp G sharp at the same time as that of forked F flat provided the right hand fingers are also raised can obviously be obtained also on a large number of musical instruments because it is evident to any one skilled in the art to which the present invention relates that the mechanisms hereinbefore described are capable of considerable and numerous modifications without

departing from the nature of the invention.

What I claim is:

1. An improvement in keyed wind musical instruments, such as clarinets and the like, comprising a normally raised pad for C sharp G sharp opening, a normally raised ring for the forked E flat forked B flat opening, and means connecting the pad and ring to cause the said pad to close its opening when said ring is depressed.

2. An improvement in keyed wind musical instruments, such as clarinets and the like, comprising a normally raised pad for C sharp G sharp opening, a normally raised ring for the forked E flat forked B flat opening, means connecting the pad and ring to cause the said pad to close its opening

when said ring is depressed, and a key for independently raising said pad when said ring is depressed.

20

3. An improvement in keyed wind musical instruments, such as clarinets and the like, comprising a normally raised pad for C sharp G sharp opening, a normally raised ring for the forked E flat forked B flat opening, means connecting the pad and ring to cause the said pad to close its opening when said ring is depressed, and means connecting said pad with the rings operated by the fingers of the right hand to depress said pad when any of said rings for the right hand is depressed.
